(57) **CLAIM**

The ornamental design for an LED component, as shown and described.

DESCRIPTION

FIG. 1 is a top, front and left side perspective view of an LED component showing my design;

FIG. 2 is a front elevation view thereof;

FIG. 3 is a rear elevation view thereof

FIG. 4 is a left side elevation view thereof

FIG. 5 is a right side elevation view thereof;

FIG. 6 is a top plan view thereof;

FIG. 7 is a bottom plan view thereof; and,

FIG. 8 is a bottom, front and right side perspective view thereof.

The broken line showing in the embodiments of FIGS. 1-8 are for illustrative purposes only and forms no part of the claimed design. The top layer can have be visually transparent or translucent as shown in the embodiments of FIGS. 1-8.
